UNITED STATES PATENT OFFICE.

JOHN W. SYKES, OF CHICAGO, ILLINOIS.

DITCHING AND EARTH-DISTRIBUTING MECHANISM.

941,050.

Specification of Letters Patent. Patented Nov. 23, 1909.

Application filed March 2, 1908. Serial No. 418,791.

To all whom it may concern:

Be it known that I, JOHN W. SYKES, a citizen of the United States, residing at Chicago, in the county of Cook and State of Illinois, have invented a new and useful Improvement in Ditching and Earth-Distributing Mechanism, of which the following is a specification.

My invention relates particularly to machines for cutting channels or ditches and distributing the spoils over the land, whereby the formation of spoils-banks adjacent to the ditches is obviated.

My primary object is to provide thoroughly practicable means for distributing over land the spoils taken from ditches during the formation thereof, thereby rendering all of the land tillable and facilitating the passage to the drainage ditches of any water which may fall upon the land.

It may be stated here that my improved mechanism is particularly adapted for use in regions where a great deal of low marshy land abounds; and, commonly, such districts are subject to very heavy rain falls, thereby rendering it exceedingly important that provision be made for enabling the surface water to pass quickly into the drainage ditches. So far as I am aware, no provision has heretofore been made, in connection with a traction-ditching machine, for the distribution of the spoils over the land, thereby obviating the formation of spoils-banks adjacent the drainage ditches; and, it is to be borne in mind, that once the spoils-banks are formed in the regions for which my apparatus is particularly adapted, it is an exceedingly laborious and expensive operation to distribute the spoils over the land, as, for instance, by the use of scrapers.

In locations where the land is quite swampy or marshy, it is desirable to locate small drainage channels in substantial parallel relation, at distances apart varying from 75 to 200 feet. It will readily be understood, therefore, that a very great waste of ground results from the formation of spoils-banks adjacent to the ditches, and a still greater objection arises from the fact that the ditches, in such case, do not effectually perform their function. Ordinarily, moreover, each ditch is intended to drain the land on both sides of it for one-half the distance between ditches; so that where the

spoils-bank is formed, the result obtained is in reality little better than provision for drainage of one-half the land. My invention obviates the difficulties suggested, and renders it perfectly feasible to cut drainage channels and distribute the spoils at moderate expense, thereby rendering it possible to reclaim large areas of marshy land which have hitherto been irreclaimable, owing to the large expense incident to the provision of drainage means.

My invention is illustrated in its preferred embodiment in the accompanying drawings, in which—

Figure 1 represents a side elevational view of ditch-cutting and earth-distributing mechanism constructed in accordance with my invention; Fig. 2, a sectional view taken as indicated at line 2 of Fig. 1 and showing the mechanism for distributing the spoils; Fig. 3, a broken sectional view illustrating a modified form of mechanism for distributing the spoils; Fig. 4, a plan view of the mechanism shown in Fig. 3; Fig. 5, a broken plan view showing details of the gearing employed in the construction shown in Fig. 1; Fig. 6, a view illustrating the relation of the drainage channels, and illustrating my mechanism in the course of forming the channels; Fig. 7, a broken sectional view of the earth, showing the manner in which the spoils-banks are located, according to old methods; and Fig. 8, a similar section, illustrating the manner in which the spoils are distributed in the use of my improved mechanism.

In the construction shown in Figs. 1, 2 and 5, A represents the main frame of a traction ditching-machine; A¹, traction mechanism of well-known construction, particularly adapted for traveling over soft marshy ground; B, a cutter-wheel frame adapted to be raised and lowered with relation to the main frame, in a well-understood manner; B¹, a channel-cutting and earth-elevating wheel of well-known construction; and C, mechanism serving to receive the spoils and distribute the same over the land. The ditching-machine may be of any desired type and construction. Several machines adapted to the purpose of cutting channels through land are on the market, and it is unnecessary, in the present application, to explain details of construction of

such machines, further than may be necessary for understanding my invention.

In the machine illustrated, the traction mechanism A¹ includes traveling aprons, 5 such, for instance, as are shown in patent to Hill, No. 866,647, granted September 24, 1907. Upon the main frame is mounted a motor a having a shaft a⁴ (Figs. 1 and 5). The shaft a¹ is equipped with a shiftable 10 pinion a² splined on the shaft and capable of being shifted by means of a lever a³. The pinion a² may be thrown into mesh with a gear a⁴ on a shaft a⁵. The shaft a⁵ is connected, by means of sprocket-wheels and a 15 sprocket-chain a⁶, with a shaft a⁷. The shaft a⁷ is further equipped with a shiftable clutch-member a⁸ splined on the shaft and adapted to be moved by means of a lever a⁹. The clutch a⁸ may be shifted to throw into 20 operation a sprocket-wheel a¹⁰ journaled on the shaft a⁷. A sprocket-chain a¹¹ connects the sprocket-wheel a¹⁰ with a sprocket-wheel a¹² secured to a shaft a¹³. The shaft a¹³ is 25 further equipped with a sprocket-wheel a¹⁴ which is connected by a sprocket-chain a¹⁵ with a wheel a¹⁶ forming a part of the traction mechanism A¹. It will be understood that similar provision is made at the other side of the machine (not shown) for operating the endless apron thereat.

The wheel B¹ is equipped with cutting and elevating blades, or buckets, b, which operate to cut the channel and dump the dirt upon a conveyer b¹ which serves to deliver the dirt laterally at one side of the wheel, in a well-understood manner. The spoils-distributing mechanism C comprises a trough, or spout, c, supported on a pivot c¹, and having at its base a hopper c² into 35 which the spoils are delivered from the conveyer b¹; a cable c³ attached to the spout c and passing about a pulley c⁴, said cable serving as a means for oscillating the chute or spout c in the operation of the machine; 40 a wheel c⁵ connected by a sprocket-chain a⁶ with the shaft a⁷ and equipped with a crank c⁷ with which the cable c³ is connected; a pump c⁸ operated by a sprocket-chain, or belt, c⁹ connected with the shaft a⁷; a suction-hose c¹⁰ connected with the pump and supported in position to enable its free end to depend into the ditch cut by the wheel B¹; and a pressure-hose c¹¹ connected with the pump and equipped with a nozzle c¹² 45 which extends through the base-portion of the spout c in alinement with the axis of the spout, as shown in Fig. 2.

The earth-cutting and elevating wheel B¹ is actuated through the medium of a shaft d¹ 60 which is connected by a sprocket-chain d¹ with the shaft a⁷. The manner of operating the cutter-wheel is well understood in the art.

In the usual operation of a traction ditching-machine like the one illustrated, pro-

vision is made for the continuous forward travel of the machine, the cutter-wheel operating continuously, during the forward movement of the machine, to cut the channel and elevate the earth. In some cases, the 70 operation is such that the cutter-wheel is lowered to cut a channel, it is then elevated, the machine then moved forward a distance equal to approximately one-half the diameter of the cutter-wheel, and the cutter-wheel then fed downwardly, so that the machine progresses by a step by step movement. However, my invention is applicable to any traction ditching-machine where it is desirable to distribute the spoils over the land 80 during the process of forming the ditch.

It will now be understood that the crank-wheel c⁵ imparts a continuous up and down oscillation to the spout c, while the pump c⁸ operates continuously to draw water from 85 the ditch in the rear of the machine and force the water thus drawn through the nozzle c¹² and spout c. The soil delivered by the conveyer b¹ is dropped into the base-portion of the spout c directly in front of the 90 nozzle c¹², and is projected at high velocity from the spout c. It will be understood, therefore, that inasmuch as the spout c oscillates up and down the material will be 95 distributed over the land with more or less 95 uniformity, covering a considerable area of the land at some little distance from the drainage ditch. Where a powerful enough 100 pump is employed and the drainage channels are not too widely separated, the dirt may be deposited over substantially the full area between ditches. In this connection, it is to be borne in mind that, owing to the texture and composition of the earth commonly encountered in low land districts and 105 owing to the large volume of water which would ordinarily be employed in the distributing operation, the earth being distributed will be largely disintegrated and held in suspension in the water and will flow over 110 the surface of the land, even after the material issuing from the spout has encountered the earth.

In the modification illustrated in Figs. 3 and 4, I employ a rotary soil-scattering member f which is located beneath the outer end of the conveyer b¹ and receives the material therefrom. The member f is rotated at high speed, through the medium of any suitable means, and operates to scatter the spoils over the surface of the land. In the modification illustrated, the member f is equipped with rows f¹ of paddles, or blades, which incline in a direction reverse to the direction of rotation of the wheel. The paddles, or blades, of the successive rows are staggered with relation to each other, as illustrated in Fig. 4. Provision is made for imparting a varying velocity of rotation to the rotary member f, thereby pro-

viding for variation in the force with which the material is hurled from the wheel, so that the material will be distributed over a large area. Any suitable means for imparting variable speed may be employed.

5 I have shown the shaft f^2 of the rotary member equipped with a cone-pulley f^3 which is connected by a belt f^4 with a cone-pulley f^5 operated by a chain, or belt, f^6 . A belt-shifter f^7 is connected with the belt, and it will be obvious that the speed of rotation of the member f may be varied by shifting the belt f^4 upon the cone-pulleys mentioned.

10 In Fig. 6, I have shown a number of parallel drainage ditches g which communicate with a larger ditch g^1 .

15 In Fig. 8, I have illustrated, by cross-section, the manner in which the spoils are distributed to form a layer g^2 . In this connection, it may be stated that a double advantage is derived from this distribution of the spoils over the surface of the land, since a firmer soil results from the scattering of the clay sub-soil taken from the ditches over 20 the surface of the land which is largely composed of decayed vegetable matter. Moreover, the sub-soils thus deposited over the surface of the land furnishes those elements necessary for agricultural purposes in which 25 the surface soils of marshy land are deficient.

30 In the section shown in Fig. 7, the spoils from the ditches g are illustrated as deposited in spoils-banks g^3 according to the old methods. It will at once be evident that not only is there great economic waste in the use of the old method, owing to the fact that a large proportion of the land is left untilable, but that, moreover, imperfect drainage 35 results.

40 My improved apparatus renders it perfectly feasible to distribute the spoils derived from drainage ditches over the land adjacent to the ditches in such manner as to 45 render the land tillable throughout its whole area, and this result may be attained at very little additional expense over that involved in making ditches with the apparatus now in common use. It is obvious that the land 50 is thus very greatly enhanced in value, and the importance of my invention will be readily appreciated by those who have had experience in the reclaiming of the low lands of our country.

55 It is to be understood that I have merely illustrated the preferred forms of my invention, and I have described the same in detail for clearness of understanding only. Hence, no undue limitation is to be understood from the description given.

60 What I regard as new, and desire to secure by Letters Patent, is—

65 1. In a ditching-machine, the combination with traveling channel-cutting and earth-elevating mechanism, of spoils distributing

mechanism carried therewith and operative to receive the earth from said first-named mechanism and spread the same over the land, thereby obviating the formation of spoils-banks adjacent the channel.

70

2. In a ditching-machine, the combination with traveling mechanism operative to cut a channel and deliver the earth laterally at a distance above the ground, of scattering mechanism carried therewith operative to receive the spoils from said first-named mechanism and spread the same over the land.

75

3. In a ditching-machine, the combination with traction mechanism, of channel-cutting and earth-elevating mechanism mounted to be carried thereby, and spoils distributing mechanism having means operative to vary automatically the distance of the deposition of the material from the channel, whereby 85 the spoils will be spread over the land, for the purpose set forth.

80

4. In mechanism of the character set forth, the combination with means for cutting a channel in the earth and elevating the material, of hydraulic mechanism operative to 90 distribute the spoils over the land.

90

5. In mechanism of the character set forth, the combination with means for cutting a channel in the earth and elevating the material, of hydraulic distributing mechanism, including a spout into which the material is deposited, and means for forcing water through said spout.

95

6. In mechanism of the character set forth, 100 the combination with an earth-cutting and elevating wheel, of a lateral conveyer, distributing mechanism receiving the material from the lateral conveyer, and means operative to vary the-throw of the material from 105 the machine, whereby the material will be distributed in a layer over the land.

100

7. In mechanism of the character set forth, the combination with channel-cutting and earth-elevating mechanism, of a movable 110 spout serving to receive the material, and fluid-pressure means connected with said spout.

110

8. In mechanism of the character set forth, the combination of channel-cutting and 115 earth-elevating mechanism, of a spout serving to receive the material, and means for forcing a fluid jet through said spout, whereby the material will be hurled from the spout and distributed in a layer upon the 120 land.

115

9. In mechanism of the character set forth, the combination with channel-cutting and earth-elevating mechanism, of a spout serving to receive the material, and means for 125 oscillating said spout in a vertical plane.

125

10. The combination with mechanism adapted to travel over land and equipped with channel-cutting and earth-elevating means, of means carried therewith for deliv- 130

ering the spoils laterally at one side of the machine, and means for throwing the spoils in a shower over the land.

11. The combination with mechanism adapted to travel over land equipped with channel-cutting and earth-elevating means, of means for delivering the spoils laterally, and jet mechanism carried therewith and adapted to throw the spoils in a shower upon

10 the land.

12. In mechanism of the character set forth, the combination with mechanism for

cutting a channel and elevating the earth, of means for receiving the spoils, and a pump equipped with an intake pipe adapted 15 to depend into the ditch formed by the machine and equipped with an outlet pipe adapted to serve in delivering water for use in distributing the spoils.

JOHN W. SYKES.
